ENGINE FOR DELIVERING COMPRESSED AIR AND POWER

Filed July 11, 1929.

GEORGE ROLFE STOW
INVENTOR;

By *Oto Munk*
his Attorney.

UNITED STATES PATENT OFFICE

GEORGE ROLFE STOW, OF SEATON PARK, SOUTH AUSTRALIA, AUSTRALIA

ENGINE FOR DELIVERING COMPRESSED AIR AND POWER

Application filed July 11, 1929, Serial No. 377,365, and in Australia July 23, 1928.

My invention relates to improvements in and connected with engines for obtaining compressed air and power. The engine hereinafter described, although in some respects similar in design to an internal combustion engine, must not be confused with that type of motor, as the invention is operated by steam so that the power is not generated in the cylinder, but is generated outside of the engine by any convenient means and is conveyed thereto by pipes.

Hitherto the machinery for compressing air has been constructed in such a manner that two separate elements have been necessary to compress and expel the air, viz:—a prime mover such as an internal combustion engine or other means for developing power, and a separate air compressor which is driven by the prime mover for delivering air for use outside the cylinder as for instance to an accumulator or to a pneumatically operated machine.

With my invention I am able to compress air on one side or on both sides of the piston, but whether one or both sides of the piston are used for compressing air I mount both a steam inlet and a compressed air outlet in the cylinder on the same side of the piston, or in other words I use one side of the piston both for power and compressing purposes by admitting steam when the piston is on the centre at the end of the stroke; cutting off steam at a predetermined point, allowing the steam to expand as is usual on an ordinary steam engine, exhausting the steam to atmosphere or to another engine near the end of the stroke, and according to design or adjustment, simultaneously or nearly simultaneously admitting the scavenging air to the cylinder above the piston which expels the exhaust steam and fills the cylinder with fresh air.

The momentum of the fly wheel carries the piston round the dead centre and causes the commencement of the up stroke whereby the scavenging opening or openings are closed, and during the remainder of the stroke air which has been admitted remains in the cylinder after the exhaust steam has been scavenged out and the exhaust opening has been

closed. The air is compressed and expelled during the completion of the cycle, after which fresh steam enters the cylinder and repeats the above described series of operations.

It is of course essential in the design of the machine that the setting of the steam valve be so arranged that the quantity of steam admitted will be sufficient to develop more power than will be required for compressing the air to the desired pressure and also for subsequently expelling the air, and if so desired to additionally drive any machinery which may be connected to the engine.

Obviously the adjustment and timing of the valves will vary according to requirements and must be calculated according to the use to which the compressor is to be applied.

I will now describe my invention as constructed and applied to an engine in which only one side of the piston is used for the double purpose of compressing air and supplying power by aid of the accompanying drawings wherein:—

Fig. 1 is a front elevation of my device in part section.

Fig. 2 is a side elevation of Fig. 1 in part section.

Fig. 3 is a plan showing upper portion of Fig. 1.

Figs. 4, 5 and 6 are sectional illustrations of valves suitable for use in my device. These valves present no feature of novelty.

In each of the illustrations similar letters of reference are used to denote similar or corresponding parts wherever they occur.

In the drawings *a* is a cylinder fitted at its upper end with a cover *a'*, the cylinder being adapted to rest upon a cylindrical portion *b'* of a main casting or crank case *b*.

Within the main casting I provide bearings *c* suitable for the support of the crank shaft and crank *d* upon which a fly wheel *e* may be supported.

I also mount on the crank a connecting rod *f* of any suitable design and a gudgeon pin *f'* for a reciprocating piston *g*.

The piston *g* is operated by steam from

some external source of supply which is admitted to the cylinder through a suitable steam intake or valve h . This valve may vary in design, but a suitable form is shown in Fig. 6 of the drawings.

This intake valve for the admission of the steam is preferably operated by a mechanical device such as hereinafter more fully described. The steam is admitted under pressure and acts expansively as in an ordinary steam engine and drives the piston to its lowest position within the cylinder, the steam being cut off at a predetermined point. The steam is exhausted to atmosphere or to another engine when nearing the end of the down stroke of the piston.

An exhaust valve of suitable device is shown at j in Figs 1, 2 and 3, and also in Fig. 4 of the drawings, and when the piston is approaching the position illustrated in Figs. 1 and 2 of the drawings scavenging air is admitted to the cylinder immediately above the piston.

This scavenging air is under a slight pressure and in the type of engine shown in the illustrations is obtained from the crank case through the outlet h from whence it passes through the pipe h' and enters the cylinder above the piston through the ports $h2$, a very fine spray of water being simultaneously admitted through the pipe and spray nozzle l , to keep down the temperature of the air thereby reducing the power which is required to compress it and at the same time acting as a substitute for a water jacket. The scavenging air expels the exhaust steam through the exhaust valve j , the upward stroke of the piston closes the ports $h2$ and cuts off the supply of scavenging air. Simultaneously or almost simultaneously the valve j is closed.

When the exhaust outlet j is closed the upward return stroke of the piston continues so that the piston compresses the remaining air and forces it under compression through the air valve n until the cycle is completed. The expelled compressed air is delivered to its required destination and fresh steam enters the cylinder and commences another cycle.

The compression of the air heats the cylinder walls and cover to a temperature suitable for the admission of steam for each succeeding stroke, thus adding to its efficiency by preventing initial condensation, and, moreover, the small quantity of air which remains in the cylinder at the end of the stroke mixes with the newly admitted steam and acts as a power immediately the piston has passed the dead centre.

It is to be distinctly understood that the momentum of the fly wheel carries the piston upwards and round the dead centre and it is therefore essential that in the design of the machine the setting of the steam valve should

be so arranged that the quantity of steam admitted will be sufficient to develop more power than will be required for compressing the air to the desired pressure and also for subsequently expelling the air, and if so desired the steam supply may be further increased to enable it to additionally drive any machinery which may be connected with the engine.

To supply the necessary air for scavenging purposes I fit an air valve o in the crank case, such valve being adapted to close under pressure, but to supply the crank case with air by suction whilst the piston is travelling upwards. Such an arrangement is suitable to the design of engine shown in the accompanying drawings, but the air supply may be contributed by other means without departing from the nature and principle of my invention.

In order to operate the valve h and j I use rods h' and j' which are mounted in suitable bearings. The valves are provided at their upper ends with short operating spring governed guide stems $h2$ and $j2$. Levers p are designed to engage the valve stems and are fulcrumed on a support or bracket q and connected to the rods h' and j' , the lower ends of which are designed to be operated by cams which are timed to rotate in such a manner as will give effect to the above described cycle of movements.

For this purpose I may arrange a train of tooth wheels r which derive primary motion from the main shaft and transmit it to a cam shaft s . Upon the cam shaft the cams t and t' are supported and adjusted and transmit motion to rods h' and j' by means of the cams, one of the rods j' may be direct acting and working upwards whilst the other h' is fitted with a connecting bridle $h3$ and operated by downward movement.

In the foregoing specification I have described a single acting compressor and engine, but the principles herein disclosed may be applied so as to act on both sides of a piston of suitable design which is similarly accommodated within a suitable cylinder to which any known method of supplying scavenging air is used and of exhausting the contents of the cylinder is effected.

In air compressors as at present in use loss of efficiency occurs through the compressed air which fills the clearance spaces and consequently has to expand on the suction stroke of the piston to the pressure of the incoming air before the incoming air enters the cylinder, but in my device a power stroke—not a suction stroke—follows the compression stroke, and consequently the above indicated losses are avoided.

A further economy is obtained in my device by the use of the water spray previously referred to, whereby water enters into the air in the form of a mist which absorbs most

of the heat of the compression so that the compressed air leaves the compressor at approximately the same temperature as saturated steam at that pressure.

Having now fully described and ascertained my said invention and the manner in which it is to be performed, I declare that what I claim is:—

1. In a reciprocating engine, the combination of a piston, a cylinder therefor having a steam inlet port and a compressed air outlet port on the same side of the piston head, and a valve for each port coacting to alternately actuate the piston by steam on the initial stroke and to compress and expel the compressed air on the return stroke.

2. A reciprocating engine as claimed in claim 1, including an air pipe connected to the cylinder to admit air at low pressure for scavenging exhaust steam above the piston at or near the end of the steam stroke.

3. A reciprocating engine as claimed in claim 1, including means for timing and controlling the valves for the admission of steam and the compression of air to avoid the expansion of any compressed air which remains in the clearance space of the cylinder to the pressure of the incoming air.

In testimony whereof I affix my signature.

GEORGE ROLFE STOW.
